(12) **United States Design Patent** (10) **Patent No.:** **US D1,010,133 S**
(45) **Date of Patent:** **** Jan. 2, 2024**

(54) **ANALYTE SENSOR ASSEMBLY**(71) Applicant: **ABBOTT DIABETES CARE INC.**,
Alameda, CA (US)(72) Inventors: **Philip Yee**, San Francisco, CA (US);
Samuel Mason Curry, Oakland, CA (US)(73) Assignee: **ABBOTT DIABETES CARE INC.**,
Alameda, CA (US)(**) Term: **15 Years**(21) Appl. No.: **29/684,719**(22) Filed: **Mar. 22, 2019****Related U.S. Application Data**

(63) Continuation of application No. 14/841,122, filed on Aug. 31, 2015, now abandoned, and a continuation of application No. 14/841,429, filed on Aug. 31, 2015, now abandoned, and a continuation of application No. 14/841,224, filed on Aug. 31, 2015, now Pat. No. 10,492,685, said application No. 14/841,429 is a continuation of application No. 12/807,278, filed on Aug. 31, 2010, now Pat. No. 10,136,816, said application No. 14/841,122 is a continuation of application No. 12/807,278, filed on Aug. 31, 2010, now Pat. No. 10,136,816, said application No. 14/841,224 is a continuation of application No. 12/807,278, filed on Aug. 31, 2010, now Pat. No. 10,136,816.

(60) Provisional application No. 61/299,924, filed on Jan. 29, 2010, provisional application No. 61/291,326, filed on Dec. 30, 2009, provisional application No. 61/256,925, filed on Oct. 30, 2009, provisional application No. 61/247,508, filed on Sep. 30, 2009, provisional application No. 61/247,519, filed on Sep. 30, 2009, provisional application No. 61/247,514, filed on Sep. 30, 2009, provisional application No. 61/238,581, filed on Aug. 31, 2009.
